GEORGE CROMPTON, OF WORCESTER, MASSACHUSETTS.

Letters Patent No. 69,974, dated October 22, 1867.

IMPROVEMENT IN WEFT-STOP-MOTION FOR LOOMS.

The Schedule referred to in these Letters Patent and making part of the same.

TO ALL WHOM IT MAY CONCERN:

Be it known that I, GEORGE CROMPTON, of Worcester, in the county of Worcester, and State of Massachusetts, have invented an Improvement in Looms; and I do hereby declare that the following, taken in connection with the drawings which accompany and form part of this specification, is a description of my invention sufficient to enable those skilled in the art to practise it.

The invention relates to the construction and arrangement of mechanism in looms for automatically stopping the loom whenever the shuttle-thread or weft breaks, and the invention consists in the employment of a series of fingers, on a tilting-arm hung upon the lathe, in connection with another set of fingers which, at each time the lay beats up, are carried down into line with the first set, the chute being thrown across and directly over the first set, so that, when the others come down upon the thread, they tend to press it down between the tilting-fingers. If the thread is whole, it will be strained so tightly over the lower fingers that the pressure of the upper ones will carry down both sets together; but if the thread is broken, then the upper set carries the loose thread down between the lower ones without tilting them, in which position a pin, on a tail-piece projecting from the tilting-fingers, is struck by a pin on a rocker-lever which carries the upper fingers, and is carried back, such back movement effecting the withdrawal of a tooth from a sliding-plate in front of the lathe, liberating such plate, which, at such liberation, moves endwise, causing another plate to which it is connected to tip, this latter plate having a hole or slot into which a pin on the shipper-lever moves if, when the lay beats up, the thread is unbroken, but by the movement of which (effected by the withdrawal of the tooth) it is brought into such position that the pin on the shipper-lever strikes its face, throwing the lever out of its notch, thereby slipping the belt and stopping the loom; this taking place whenever the weft is broken.

It is in such a construction and arrangement that the invention consists, and the drawings represent the parts of a loom with which these devices are connected, and by which they are operated.

A denotes a plan of the loom, B a cross-section of the same, C a front view of the batten-bar.

a denotes the loom-frame; b the lathe, driven by the shaft c', in the usual manner; c is the batten-bar, over which the shuttle flies; d the breast-beam. On the front face of the bar c, at or near each end, is a slide-plate, e, the two being connected by a rod, f, and supported on teeth, g, projecting out through the bar c, and the plates are guided, as they slide, by these teeth and guide-plates h. The plate e, at one of the lathe, is connected by a pin, i, with a rocker-plate, k, hung upon a pin, l. This rocker-plate has a hole, m, which, at every beat-up of the lathe, (when the weft-thread is unbroken,) comes opposite to and is entered by a pin, n, on the shipper-lever o. But if, when the lathe beats up, the rocker-plate shall vary at all from its normal position, the pin n will then be struck by the face of the plate, (instead of entering the hole m,) and the shipper-lever will be thereby pressed out from its notch. Each tooth, g, projects from a sliding carriage, p, working through the bar c, and in this carriage a tilting-block, q, is hung on a pin, r, this block having a set of fingers or prongs, s, projecting from its front end, and having a pin, t, projecting laterally from its rear end, as shown at B. Each carriage is pressed forward and held in normal position by a spring, w. v denotes a rocker-lever, hung upon a bracket, u, at each end of the lathe. The front arm of each lever v has prongs or fingers x projecting from it, and its rear arm y is weighted so as to hold these fingers x (normally) up above the bar c. The rear end of the lever is curved downwards, or has a tail-piece, z, and, as the lay beats up, this tail-piece strikes a stud, d'; (extending from a bracket or projection on the frame a,) tipping up the rear end of the lever, and carrying the fingers x down, between the fingers s, into the bar c. An arm, c', projecting down from the lever v, carries a pin, d', and, as the lay beats up, if the fingers x go down between the fingers s without communicating any movement thereto, this pin d' will strike the pin t, on the block q, and will drag back such block and the slide p, and its tooth g, the drawing in of the two teeth g liberating the slides e.

The operation of the mechanism is as follows: The shed having been formed, the shuttle is thrown, and the chute passes directly over the fingers s. As the lay beats up, the fingers x are thrown down by the lever v, striking the stud d'; and, as they descend into the batten-bar, they carry with them the thread, which, lying taut, or approximately so, upon the fingers s, carries them down with it, tilting up the rear end of the block q, and carrying its pin out of the path of movement of the pin d' on the rocker-lever, so that no relative rear movement of the block q or teeth g takes place. If, however, the weft-thread breaks, and lies loosely across

the fingers s , or gives out, or does not extend across them, then the fingers x will be carried down between the fingers s , (as the lay beats up,) without imparting corresponding movement thereto; and then the pins d' , striking the pins t , drag back the slide p , and their teeth g , and liberate the slides c , which liberation allows the heavy end of the plate k to drop, carrying the hole m out of line with the shipper-lever pin n , so that the face of the plate strikes the pin and forces the lever from its notch, causing it to spring over, shift the belt, and stop the loom.

I claim, in combination with the sets of fingers or prongs between which the chute passes, the mechanism by which, through their action, the shipper-lever is released when the thread is broken, substantially as set forth.

GEO. CROMPTON.
